BUILDING FOR LIQUID STORAGE

Oscar Janssen, St. Louis, Mo., assignor to Oscar Janssen Stainless Steel Tanks, Inc., St. Louis, Mo., a corporation of Missouri

Application March 31, 1950, Serial No. 153,271

6 Claims. (Cl. 72—1)

1

This invention relates to buildings for liquid storage and more particularly to beer cellars for storage of beer.

The object of the invention is the provision of a building for storage of liquid, in particular a beer cellar for storage of beer, which has a high storage capacity relative to its cost and which may be relatively quickly erected. The building is of multiple-story poured concrete construction. In each story there is a row of liquid storage chambers each of which is formed by an elongate tank of generally rectangular cross-section having exteriorly reinforced top, bottom, side and end walls of relatively light gage non-corrosive sheet metal such as stainless steel. The tanks in each story are arranged horizontally side-by-side and spaced apart with the tanks in successive stories located directly above those below. Each tank is embedded in concrete poured around its top, sides and ends, the concrete covering the tops of tanks in a particular story forming a continuous floor for the row of tanks directly above in the next story. The building is constructed with spaces extending the length of the chambers between the concrete sides of adjacent chambers of each row, these spaces forming passages for flow of air between the sides of adjacent chambers for cooling purposes, in the case of beer storage. Other features will be in part apparent and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawings, in which one of various possible embodiments of the invention is illustrated,

Fig. 1 is a vertical longitudinal section through a building of this invention, taken on line 1—1 of Fig. 2;

Fig. 2 is a vertical transverse section taken on line 2—2 of Fig. 1;

Fig. 3 is a fragmentary vertical transverse section taken on line 3—3 of Fig. 1;

Fig. 4 is a horizontal section taken on line 4—4 of Fig. 1;

Fig. 5 is an enlarged fragmentary vertical longitudinal section taken on any one of lines such as 5—5 of Fig. 3; and,

Fig. 6 is an enlarged fragmentary vertical longitudinal section taken on any one of lines such as 6—6 of Fig. 3.

Similar reference characters indicate corre-

2

sponding parts throughout the several views of the drawings.

Referring to the drawings, a building of this invention is designated 1 in its entirety. The building is of multiple-story construction, having ten stories as herein illustrated. It will be understood that the number of stories may be varied. The front and rear of the building are designated 3 and 5, respectively. The left side wall, as viewed from the front is designated 7, and the right side wall is designated 9.

In each story is a row of liquid storage chambers A, nine being shown in row. Each of these is formed by an elongate tank 11 of generally rectangular cross-section having top, bottom, side and front and rear end walls 15, 17, 19, 21 and 23, respectively, of relatively light gage non-corrosive sheet metal, such as 18 gage stainless steel. All walls of each tank are exteriorly reinforced by a mesh 25 of reinforcing bars welded to ribs 27 welded to the outside of the walls (Figs. 5 and 6). The tank construction per se is fully disclosed in my copending application entitled Prefabricated Metal Tank for Use as a Lining in a Concrete Tank, Serial No. 153,272, filed March 31, 1950. This particular system of reinforcing the tank is not essential to the invention claimed herein, and it is contemplated that other systems of reinforcing may be used.

The tanks in each story are arranged horizontally side-by-side and spaced apart with the tanks in successive stories located directly above those below. The front walls of the tanks are spaced from the front of the building so that, in each story, there is a longitudinal corridor 29 at the front of the row of tanks in each story. The rear walls of the tanks are spaced from the rear of the building, as indicated at 31, at the rear of the row of tanks in each story. The end tanks at the left ends of the rows are spaced from the left side 7 of the building so as to provide rooms 33 for air cooling equipment, generally designated 35. Each of rooms 33, as herein illustrated, is two stories high. The end tanks at the right ends of the rows are spaced from the right side wall 9 of the building so as to provide transverse corridors 37 in each story at the right end of the building.

All the tanks are embedded in concrete C, poured around the tops, sides and ends of the tanks. In the course of construction of the building, reinforcement (not shown) for the first floor of the building is set in place and the first floor is poured and allowed to set. The first floor tanks, which have been prefabricated, and al-

ready have their reinforcing bars 25 welded thereon, are then set in position on the first floor. The space between the bottoms of the tanks and the first floor is grouted. This may be done either with a grout gun after the tanks have been set on the floor, or by spreading grout on the floor and setting the tanks in the wet grout.

The tanks are arranged in spaced-apart relation and forms (not shown) such as to provide rectangular spaces 39 between adjacent tanks extending the full height of the tanks and wide enough for a man to pass through are set up in place between the sides of adjacent tanks. Suitable reinforcement (not shown) is set between the forms and the sides of the tanks. Also, forms are set in place spaced from the ends and from the front and rear of the row of tanks. In setting up the forms and reinforcement, it is desirable first to set one end tank of the row in place on the floor, set the reinforcement at the sides of this tank, then the form for the space at the side of the tank, then the side reinforcement for the next tank in the row, and then to place the next tank in the floor, and so on for the length of the row. By this method, ample working room is provided. After the side reinforcement and forms have been set, the second floor reinforcement (not shown) is set on the top of the first row of tanks, and concrete is poured between the sides of adjacent tanks, between the forms at the ends of the row and the sides of the end tanks of the row, between the forms at the front and rear of the row, and upon the tops of the tanks in the row to embed all the tanks in concrete and to form the second floor. The concrete is preferably poured in successive steps, rather than to a full story height in one pouring, to reduce the hydrostatic pressure of the poured concrete on the tanks. After the second floor has set, the process is repeated up to the uppermost story.

The forms which are set in place between the sides of adjacent tanks are provided with horizontal members for forming horizontal grooves 41 at the sides of the spaces 39 at the mid-height of these spaces. After the concrete poured around the tanks has set, horizontal forms 43 are set in place resting on the shoulders 45 at the bottom of these grooves and concrete is poured on the forms 43 to provide horizontal partitions 47 dividing the spaces 39 into upper and lower passages 49 and 51 respectively. Each partition extends from the rear end toward but terminating short of the front end of the space 39 so as to leave an opening 53 at the front end of the space 39 for communication between the upper and lower passages. The horizontal partitions 47 key into the grooves 41 and, in addition to dividing the spaces 39 into passages 49 and 51, act as struts taking the side thrust of the hydrostatic load of liquid in the storage chambers. The forms 43 remain in place.

The passages 49 and 51 serve as ducts for flow of cool air supplied by air cooling equipment 35 to maintain the contents of the liquid storage chambers cool. To provide supply and return headers for the passages, each of the spaces 31 at the rear of the tanks is divided into upper and lower header passages 55 and 57, respectively, by an intermediate floor 59 of concrete at the level of the horizontal partitions 47 for the respective row of tanks. The upper passages 49 open at their rearward ends into the upper header 55 and the lower passages 51 open at their rearward ends into the lower header 57. The upper headers 55, 75

for example, are supplied with cool air from the air cooling equipment and the lower headers 57 are utilized as return headers. With this arrangement, cool air flows from the rear of each upper passage 49 toward its front, down through the respective opening 53, and back through the respective lower passage 51 to the return header 57, as shown by the flow arrows in Fig. 3. It will be understood that the lower headers 57 may be utilized as supply headers and the upper headers 55 as return headers by interchanging the connections with the air cooling equipment to reverse the direction of flow of air.

The spaces 39 are closed at their front ends by concrete walls 61 (Figs. 3 and 4). The right ends of headers 55 and 57 are closed as by doors 63. The tanks have manholes 65 at their front ends for access to the interior of the tanks. As will be understood, the tanks have inlet and outlet pipes (not shown) which lead through their concrete encasement.

To make it possible readily to determine the location of any leaks that may occur, and to clean up any contamination between a tank and its concrete encasement, the building is constructed with weep holes for drainage of leaks, and with flush-out holes for flushing out any contamination which may result from a leak in whatever space there may be between a tank and its concrete encasement. As shown best in Fig. 5, for each tank above the first story there is a series of weep holes 67 extending diagonally through the concrete from the lower side corners of any tank to the upper side corners of the two adjacent upper passages 49 in the story below. These weep holes are spaced at intervals along the length of the tanks. They do not open into the tanks. If a tank springs a leak, the liquid will drain out between the wall of the tank and the concrete around the tank and leak out through the nearest weep hole. An inspector passing through the upper passages 49 will detect such drainage and thereby be apprised not only that there is a leak, but also as to its approximate location, so that repair is facilitated. Weep holes for the tanks in the first story lead to a basement corridor 68 (Fig. 2).

As shown best in Fig. 6, there is also a series of flush-out holes 69 extending diagonally from the lower side corners of each of the passages 51 above the first story leading to the upper side corners of the two adjacent tanks in the story below. These are spaced at intervals along the length of the tanks intermediate the weep holes 67. If a tank has leaked, after suitable repairs have been made, a workman enters the lower passage 51 nearest the leak in the story above the tank and inserts a hose in the flush-out hole nearest the leak to flush out the contamination between the wall of the tank and its concrete encasement. Flush water drains out through the weep holes in the floor below.

In an exemplary embodiment of the invention the tanks 11 are of the order of forty-five feet long, ten feet wide, and ten feet high. The spaces 39 are the same height as the tanks and are about one foot four inches wide. The concrete floor slabs and the concrete at the sides of the tanks are of the order of one foot thick. It is preferable to install the tanks sloping slightly downward toward the front, rather than perfectly horizontal, for gravity flow of their liquid contents toward the tank outlets which are located at the front.

In view of the above, it will be seen that the

several objects of the invention are achieved and other advantageous results attained.

As many changes could be made in the above constructions without departing from the scope of the invention, it is intended that all matter contained in the above description or shown in the accompanying drawings shall be interpreted as illustrative and not in a limiting sense.

I claim:

1. A building for liquid storage of multiple-story poured concrete construction wherein, in each story, there is a row of liquid storage chambers each formed by an elongate tank of generally rectangular cross-section having exteriorly reinforced top, bottom, side and end walls of relatively light gage non-corrosive sheet metal, the tanks in each story being arranged horizontally side-by-side and spaced apart with the tanks in successive stories located directly above those below, each tank being embedded in concrete poured around its top, sides and ends, the concrete covering the tops of the row of tanks in a particular story forming a continuous floor for the row of tanks directly above in the next story, the building being constructed with spaces of rectangular cross-section extending the length of the chambers between the concrete sides of adjacent chambers of each row, each of said spaces being divided into an upper and a lower passage by a horizontal partition extending through the space, with the passages in communication at one end of the space, all the upper passages in each story opening at the other end of the space into an upper header, and all the lower passages in each story opening at the other end of the space into a lower header, said headers extending transversely across the ends of the chambers.

2. A building for liquid storage of multiple-story poured concrete construction wherein, in each story, there is a row of liquid storage chambers each formed by an elongate tank of generally rectangular cross-section having exteriorly reinforced top, bottom, side and end walls of relatively light gage non-corrosive sheet metal, the tanks in each story being arranged horizontally side-by-side and spaced apart with the tanks in successive stories located directly above those below, each tank being embedded in concrete poured around its top, sides and ends, the concrete covering the tops of the row of tanks in a particular story forming a continuous floor for the row of tanks directly above in the next story, the building being constructed with spaces extending the length of the chambers between the concrete sides of adjacent chambers of each row, each of said spaces being of rectangular cross-section a full story in height and wide enough for a man to pass through and being divided into an upper and a lower passage by a poured concrete horizontal partition extending through the space midway of its height from one of its ends toward but terminating short of its other end, each passage being closed at its other end, all the upper passages in each story opening at said one end into an upper header, and all the lower passages in each story opening at said one end into a lower header, said headers extending transversely across the ends of the chambers.

3. A building for liquid storage of multiple-story poured concrete construction wherein, in each story, there is a row of liquid storage chambers each formed by an elongate tank of generally rectangular cross-section having exteriorly reinforced top, bottom, side and end walls of

relatively light gage non-corrosive sheet metal, the tanks in each story being arranged horizontally side-by-side and spaced apart with the tanks in successive stories located directly above those below, each tank being embedded in concrete poured around its top, sides and ends, the concrete covering the tops of the row of tanks in a particular story forming a continuous floor for the row of tanks directly above in the next story, the building being constructed with spaces extending the length of the chambers between the concrete sides of adjacent chambers of each row, each of said spaces forming a passage for flow of air between the sides of adjacent chambers, said building having weep holes extending diagonally through the concrete from the lower side corners of each tank above the first story to the upper side corners of the two adjacent spaces in the story below.

4. A building for liquid storage of multiple-story poured concrete construction wherein, in each story, there is a row of liquid storage chambers each formed by an elongate tank of generally rectangular cross-section having exteriorly reinforced top, bottom, side and end walls of relatively light gage non-corrosive sheet metal, the tanks in each story being arranged horizontally side-by-side and spaced apart with the tanks in successive stories located directly above those below, each tank being embedded in concrete poured around its top, sides and ends, the concrete covering the tops of the row of tanks in a particular story forming a continuous floor for the row of tanks directly above in the next story, the building being constructed with spaces extending the length of the chambers between the concrete sides of adjacent chambers of each row, each of said spaces forming a passage for flow of air between the sides of adjacent chambers, said building having weep holes extending diagonally through the concrete from the lower side corners of each tank above the first story to the upper side corners of the two adjacent spaces in the story below, and with flush-out holes extending diagonally through the concrete from the lower side corners of each of the spaces above the first story to the upper side corners of the two adjacent tanks in the story below.

5. A building for liquid storage of multiple-story poured concrete construction wherein, in each story, there is a row of liquid storage chambers each formed by an elongate tank of generally rectangular cross-section having exteriorly reinforced top, bottom, side and end walls of relatively light gage non-corrosive sheet metal, the tanks in each story being arranged horizontally side-by-side and spaced apart with the tanks in successive stories located directly above those below, each tank being embedded in concrete poured around its top, sides and ends, the concrete covering the tops of the row of tanks in a particular story forming a continuous floor for the row of tanks directly above in the next story, the building being constructed with spaces of rectangular cross-section extending the length of the chambers between the concrete sides of adjacent chambers of each row, each of said spaces being divided into an upper and a lower passage by a horizontal partition extending through the space, with the passages in communication at one end of the space, said building having weep holes extending diagonally through the concrete from the lower side corners of each tank above the first story to the upper side cor-

corners of the two adjacent upper passages in the story below.

16. A building for liquid storage of multiple-story poured concrete construction wherein, in each story, there is a row of liquid storage chambers each formed by an elongate tank of generally rectangular cross-section having exteriorly reinforced top, bottom, side and end walls of relatively light gage non-corrosive sheet metal, the tanks in each story being arranged horizontally side-by-side and spaced apart with the tanks in successive stories located directly above those below, each tank being embedded in concrete poured around its top, sides and ends, the concrete covering the tops of the row of tanks in a particular story forming a continuous floor for the row of tanks directly above in the next story, the building being constructed with spaces of rectangular cross-section extending the length of the chambers between the concrete sides of adjacent chambers of each row, each of said spaces being divided into an upper and a lower passage by a horizontal partition extending

5 through the space, with the passages in communication at one end of the space, said building having weep holes extending diagonally through the concrete from the lower side corners of each tank above the first story to the upper side corners of the two adjacent upper passages in the story below, and with flush-out holes extending diagonally through the concrete from the lower side corners of each of the lower passages above the first story to the upper side corners of the two adjacent tanks in the story below.
